POCKET IMPLEMENT

Jack Van H. Whipple, New York, and Gerald P. Kammerer, Floral Park, N. Y., assignors to Burdette E. Bostwick, South Orange, N. J.

Application October 16, 1947, Serial No. 780,130

7 Claims. (Cl. 30—162)

1

This invention is directed to a pocket implement, and more particularly to a slideable blade knife adapted to be carried in or clipped to the user's pocket. While the following description is specifically directed to a twin-bladed knife, it will be understood that in the place of a blade, any other desirable tool, such as a nail file or a pair of scissors may be used.

We have found that a knife of the type here under consideration should be characterized by two important features over and above others of perhaps lesser importance. In the first place, the knife must be sufficiently light so that when it is clipped to a breast or vest pocket, it will not cause that portion of the garment to sag. Secondly, the knife must be of sufficient sturdiness, although light in weight, that when the blade is extended for use, it is rigidly and firmly held in extended position by its surrounding casing. In many commercial forms of such knives that we have seen, the knife blade is so sloppily supported by its casing as to detract from the usefulness of the knife and substantially to impair its sales' potentialities. Then too, such a knife must be easily operable, should be inexpensive to manufacture, and should present a good appearance.

It is accordingly among the objects of this invention to provide a knife of the above nature which attains the several aforementioned ends in a thoroughly practical and efficient manner.

In accordance with one form of our invention, the knife includes a substantially U-shaped casing, the side walls of which are provided with shoulders comprising ways upon which the common shank of the twin blades is slidably supported. The casing side walls are respectively channeled throughout their length, and these channels respectively receive the opposite sides or edges of a back plate, which back plate, together with the aforementioned shoulders, form another pair of channels within the casing which slidably receive the longitudinal edges of the shank. The blade shank has an opening formed therein in which is loosely received a blade actuating and locking element. This element includes portions which extend from the shank through suitable openings formed in the back plate of the knife, which openings coact with the element to lock the blades in any one of their several adjusted positions, or to permit movement of the blades thereto. Disposed between the blade shank and the front wall of the knife casing is an elongated spring having raised portions adjacent the different locked positions of the shank, and these

2

raised portions of the spring are adapted to engage the locking element to force it into locking position relative to the back plate of the casing.

5 In the drawing, wherein we have shown one form of our knife,

Figure 1 is a side view of the knife with the blade extended from one end thereof;

Figure 2 is a plan view of the rear side of the 10 knife with portions of the back plate and the knife casing being broken away and shown in section;

Figure 3 is a fragmentary view of the knife with the back plate removed and portions of the 15 locking spring and casing broken away and shown in section;

Figure 4 is an enlarged fragmentary sectional view taken along the line 4—4 of Figure 2;

Figure 5 is a sectional view taken along the 20 line 5—5 of Figure 4;

Figure 6 is a sectional view taken along the line 6—6 of Figure 4;

Figure 7 is a sectional view taken along the line 7—7 of Figure 4;

25 Figure 8 is a sectional view taken along the line 8—8 of Figure 4;

Figure 9 is a sectional view taken along the line 9—9 of Figure 4;

Figure 10 is a sectional view taken along the 30 line 10—10 of Figure 3; and,

Figure 11 is a sectional view taken along the line 11—11 of Figure 4.

Similar reference characters refer to similar parts throughout the views of the drawing.

35 Referring to Figures 1 and 2 of the drawing, the knife comprises a substantially U-shaped casing, generally indicated at 20, comprising a front wall 21 (Figure 9), side walls 22 and 23, and a back wall or plate 24, these several walls enclosing

40 a blade unit generally indicated at 25 (Figure 2) which is operable between extended and retracted positions relative to the casing. Casing 20 is preferably an integral casting of aluminum or other light-weight material. Pivotally secured

45 to one end of the knife is an attaching clip 26, which may resemble in construction and operation that shown in the copending application of Whipple and Topa, Serial No. 731,938, filed March 3, 1947.

50 As shown in Figure 9, casing 20 has a bottom surface 27, while the inside of casing walls 22 and 23 are provided respectively with shoulders 28 and 29. Above these shoulders the casing side walls are respectively provided with channels 30 and 31, within which the longitudinal edges

55 of the shank are received.

of back plate 24 are received. These two channels, as well as shoulders 28 and 29, are co-extensive longitudinally of the knife casing, and the shoulders, together with the back plate, provide longitudinal channels 32 and 33 within which the blade unit 25 is slidably disposed (see Figure 8).

Blade unit 25 (Figure 2) comprises a pair of blades 34 and 35, which are forged integral with and extend from the opposite ends of a common shank 36. As shown in Figure 8, the width of shank 36 closely approximates the distance between the end or bottom surfaces of channels 32 and 33 (Figure 9) while the thickness of shank 36 (Figure 8) closely approximates the width of these channels. Thus it follows that the relation between the blade shank and the channels is that of a close sliding fit which is, however, free enough readily to permit sliding movement of the shank within the case while preventing any movement of the shank in the case, other than longitudinal sliding movement. Thus, whether the blade unit is in extended or retracted position, it is rigidly held against any transverse movement relative to the longitudinal axis of the casing.

As shown in Figure 10, back plate 24 comprises longitudinal edge portions 37 and 38 which lie in a general plane slightly spaced from but parallel to the general plane of the central or body portion 39 of the back plate, thus providing shank supporting surfaces 37a and 37b which are respectively juxtaposed to shoulders 28 and 29 to form channels 32 and 33 described above. It should also be noted that the offset relationship of back plate edge portions 37 and 38 to the central or body portion 39 of the back plate substantially rigidify the back plate, the edge portions thus acting in a reinforcing capacity. Thus the back plate may be stamped from relatively thin sheet metal so that while it is light in weight, it is both strong and rigid. By so forming the casing, it will appear that assembly of the blade unit and the back plate is but a simple matter, as the blade unit is easily disposed in the casing against shoulders 28 and 29, whereupon back plate 24 may be slide into position by inserting its longitudinal edges in channels 30 and 31. When the back plate has been slide into its Figure 4 position, it may be detachably secured therein by a pair of pins or screws 40 and 41 which extend respectively through holes in the casing side wall and upstruck end portions 24a and 24b of the back plate.

As shown in Figure 3, blade shank 36 is centrally apertured as at 42, and this aperture may conveniently be rectangular in form. Aperture 42 receives a blade actuating and locking member, generally indicated at 43 which, as is more clearly shown in Figure 7, comprises a body portion 44, from the bottom of which extends a peripheral flange 45 (see also Figure 4), the length and width of which exceeds the length and width of aperture 42, which limits movement of element 43 to the left, as viewed in Figure 7, by virtue of the flange abutting the bottom of shank 36. Extending from the other side of body portion 44 is a neck 46 on the end of which is carried a fingerpiece 47, the top of which is preferably knurled (see Figure 4). The opposed surfaces of fingerpiece 47 and body portion 44 (Figure 7) together with neck 46, form a pair of channels 48 and 49 in the locking element 43 for a purpose which will be hereinafter described.

As is more clearly shown in Figure 2, back plate 24 has cut therein a pair of slots 50 and 51, which

are laterally offset, as shown. Also cut in back plate 24 are end openings 52 and 53, and a central opening 54. The end openings communicate respectively with the outer ends of slots 50 and 51, the inner ends of these slots communicating with opening 54. The length and width of openings 52, 53 and 54 slightly exceed the length and width of fingerpiece 47 of the operating and locking element 43 so that the fingerpiece may readily be extended through any one of the openings. The length and width of these openings also slightly exceed the length and width of body portion 44 (Figure 7) of locking element 43, so as to be able to receive the body portion to lock the blade unit in any one of its adjusted positions.

Slots 50 and 51 are slightly wider than neck 46 of locking element 43, while channels 48 and 49 on the opposite sides of the neck are slightly wider than the thickness of back plate 24, so that the portions of the back plate on opposite sides of the slots 50 and 51 may ride therewithin.

It may now be seen that when locking element 43 is depressed into the knife casing to a point 25 where the portions of the back plate adjacent slot 50, for example, register with channels 48 and 49 of the locking element, the locking element may be moved out of whichever opening 52 or 54 it may have been in, and slid longitudinally of the back plate. This, of course, carries shank 36 and accordingly blade unit 25 with it, so that the blade unit may be moved from one adjusted position to the other. When the blade unit has been moved to the desired position, body portion 44 of locking element 43 registers with one of the aforesaid openings, e. g. opening 52, and may be extended through the opening, thus to lock the blade in the corresponding position. When locking element 43 extends through opening 54 (Figure 2) the blade unit is completely retracted within the housing. If then it is desired to extend blade 34, locking element 43 is moved transversely of the longitudinal axis of back plate 24 in opening 54, until its neck 46 (Figure 8) registers with slot 50. The locking element may then be depressed until its body portion 44 clears and underlies the back plate, so that it, together with the blade unit, may be slid longitudinally of the casing. Of course, if it is desired to extend blade 35 from the other end of the knife, the locking element is moved in opening 54 transversely of the back plate in the opposite direction so that its neck may register with slot 51. It should be noted that opening 54 is wider than openings 52 and 53 so as to permit the aforesaid transverse movements.

It is, of course, desirable that when the blade has been slid into any of its adjusted positions, the locking element operates automatically to lock the blade. Furthermore, it is desirable that the blade be held in locked position with reasonable security so that it is not released from such position through inadvertence. To this end, with reference to Figure 4, we have cut out the bottom of casing 20 to provide recesses 55, 56 and 57, between which the casing bottom is channeled, as at 58 and 59. Within these channels is disposed an elongated leaf spring, generally indicated at 60, having bent-up portions 61, 62 and 63 which respectively overlie recesses 55, 56 and 57. Spring 60 may, if desired, be secured within its channels in any suitable manner, but, in any event, the spring is preferably notched as at 64 (Figure 3) and these notches register with bosses 65, or the like, in the bottom of the casing to

preclude relative movement of the spring longitudinally of the casing, thus to maintain spring portions 61, 62 and 63 in proper operative position.

Thus the spring (Figure 4) is fixedly disposed in the casing bottom beneath the blade unit 25 with its upraised portions in such a position as to underlie openings 52, 53, and 54 in back plate 24. It accordingly follows that when the blade unit is manipulated to any one of its adjusted positions, as heretofore described, locking element 43 will overlie one or another of upraised portions 61, 62 and 63 of spring 60. Thus, for example, with the locking element overlying spring portion 61, this portion of the spring is somewhat depressed into recess 55, and accordingly exerts an upward bias on the locking element, forcing its body portion 44 into back plate opening 52 and holding it there against inadvertent release, thus to lock blade unit 25 in one of its extended adjusted positions. In like manner, spring portion 63 coacts with locking element 43 to lock the blade unit in its other extended position while spring portion 62 coacts with the locking element to hold the blade unit retracted within the casing.

To effect release of the blade unit for movement from any one of its set positions to another, locking element 43 is depressed against the force of the particular upraised spring portion with which it is in engagement, until the locking element channels 48 and 49 (Figure 7) register with the back plate to permit movement of the element into one or another of slots 50, 51 (Figure 2). It may therefore be seen that no portion of the spring directly engages any portion of the blade unit, thus permitting the blade unit to be freely slid to any one of its adjusted positions. On the other hand, one or another of the upraised spring portions engages the locking element when it is actuated into one or another of its locking positions, and this spring pressure is exerted through the locking element on the blade unit, and accordingly coacts with the casing channels to rigidly support the blade unit in any one of its adjusted positions. It also follows that movement of the blade unit is confined to longitudinal movement one way or another in the casing, so that the blade never moves transversely of the longitudinal axis of the casing, this in contradistinction to conventional practice in knives of this character. This, of course, lends to the stability and rigidity of the knife as a whole, and adds greatly to its usefulness and longevity of service.

Accordingly we have provided a knife which attains the several objects set forth hereinabove in a thoroughly practical and efficient manner.

As many possible embodiments may be made of the above invention, and as many changes might be made in the embodiment above set forth, it is to be understood that all matter hereinbefore set forth or shown in the accompanying drawing is to be interpreted as illustrative and not in a limiting sense.

We claim:

1. A knife comprising, in combination, a generally U-shaped casing comprising front and side walls, each of said side walls having a longitudinally extending blade shank supporting shoulder, each of said side walls also having a longitudinally extending channel formed therein, a blade having a shank portion slidably mounted on said shoulders, and a back plate having its longitudinal edges disposed respec-

tively in said side wall channels for retaining said shank portion on said shoulders.

2. A knife comprising, in combination, a casing having front, back and side walls, a blade having a shank portion slidably disposed in said casing, a blade actuating and locking element loosely mounted in and carried by said shank portion, said casing back wall having a longitudinal slot formed therein, said slot being widened at its extremities and at an intermediate portion thereof, the slot section between the intermediate widened portion and one of the end widened portions being out of alignment with the slot section between the intermediate widened portion and the other of the end widened portions, said element including a portion extending through said slot and a portion adapted to be received in any one of the widened portions of said slot to lock said blade in any one of its several adjusted positions, said element being movable transversely of said slot when in said intermediate widened portion so that it may be registered with one or the other of said slot sections depending on which way it is to be moved, and a spring member disposed in said casing between said front wall and said blade and adapted to engage said blade actuating element when it is in register with any one of said widened portions to force said element into blade locking position.

3. A knife in accordance with claim 1, wherein in said back plate includes longitudinal portions adjacent the edges which are disposed in said channels which with said supporting shoulders form blade shank receiving channels within which said blade shank may slide with a close sliding fit thereby to confine the blade and its shank to longitudinal movement only relative to said casing.

4. A knife in accordance with claim 1, wherein in said back plate includes longitudinal portions adjacent the edges which are disposed in said channels which with said supporting shoulders form blade shank receiving channels within which said blade shank may slide with a close sliding fit thereby to confine the blade and its shank to longitudinal movement only relative to said casing, the central portions of the inner side of said back plate being relieved and spaced from said shank so as to be completely out of engagement therewith and with said blade during the sliding movement of both.

5. A knife comprising, in combination, a casing having front, back and side walls, a blade having a shank portion slidably disposed in said casing, a blade actuating and locking element mounted on and carried by said shank portion, said casing back wall having a longitudinal slot formed therein, said element including a portion extending through said slot to a position accessible for manual operation, and a spring member disposed in said casing between said front wall and said blade, said spring member having longitudinally spaced portions adapted to engage said blade actuating element in its different adjusted positions only longitudinally of said knife for locking said blade in its adjusted position.

6. A knife according to claim 5, wherein said blade actuating and locking element is loosely mounted on the shank portion of the blade so as to be movable relative thereto in directions normal to the longitudinal axis of said blade.

7. A knife comprising in combination, a casing having front, back and side walls, a blade

having a shank portion slidably disposed in said casing, a blade actuating and locking element loosely mounted in and carried by said shank portion, said casing back wall having a longitudinal slot formed therein, said slot being widened at its extremities and at at least one intermediate portion thereof, said element including a portion extending through said slot and a portion adapted to be received in any one of the widened portions of said slot to lock said blade in any one of its several adjusted positions, and a spring member disposed in said casing between said front wall and said blade, said spring member having portions spaced from said shank portion and adapted to engage said blade actuating element when it is in register with any one of said

widened portions to force said element into blade locking position.
